Otto J. Heinzmann
INVENTOR
BY
Victor J. Evans
ATTORNEY

UNITED STATES PATENT OFFICE.

OTTO J. HEINZMANN, OF PRINCE BAY, NEW YORK.

COMMUTATOR OR TIMER.

Application filed October 9, 1920. Serial No. 415,717.

To all whom it may concern:

Be it known that I, OTTO J. HEINZMANN, citizen of United States, residing at Prince Bay, S. I., in the county of Richmond and State of New York, have invented new and useful Improvements in Commutators or Timers, of which the following is a specification.

This invention relates to commutators or timers, and the principal object is to produce a commutator of fewer parts than those now on the market.

Another object is to produce a device of this nature which shall be simple of construction, cheap to manufacture, and efficient for the purpose for which it is designed.

Another object is to produce a device of this nature which may be easily assembled and readily taken apart to replace broken and worn parts.

With these and incidental objects in view, the invention resides in certain novel construction and combination and arrangement 25 of parts the essential features of which are set forth in the following description and claims and fully shown in the accompanying drawing, in which:—

Figure 1 is a view of a standard timer 30 provided with my improvement.

Figure 2 is a perspective view of the roller retaining spring.

Figure 3 is a view of the pivot pin of the roller.

Figure 4 is a plan view of the roller holding arm per se.

Figure 5 is an elevational view of the roller holding arm per se.

Like characters of reference refer to like 40 parts in all views.

In the commutator used by the Ford car as at present constructed there are seven moving parts, and the present invention contemplates the simplifying of the structure 45 so that four parts only are used, and these are assembled without any rivets or similar parts.

Referring more particularly to the drawing, 1 represents the usual casing of a Ford 50 commutator provided with the contacts 2 seated in the fibre or other insulating member 3 and connected with respective binding posts and thumb nuts 4. The usual pull connection is shown at 5. All of these parts 55 are old and no claim is made to them except

in combination with the new mechanism hereinafter described.

Mounted on the usual rotary shaft 6 is the boss 7 of a roller arm 8. The arm 8 is slotted in at 9 and 10 so as to form a pair of fingers 11; and is formed with a pair of hooked fingers 12 between the hooks of which is defined a spring seat 13. A notch 14 is formed in arm 8 adjacent to the fingers 12.

A roller 15 is mounted to turn freely upon a pin 16 which pin is slabbed off at its ends so as to form flat faces 17 which are adapted to bear against the sides of the slot 9 when the pin 16 is inserted in said slot as shown in Figure 1. The slot 10 in which the roller 15 is inserted is extended into the body of the boss 7 and arm 8 as shown in dotted lines in Figure 4 so as to permit of insertion of said roller and of the free movement 70 of said roller when in place. The purpose of this roller is the same as of the roller in the commutator now in use, viz, to contact members 2 and complete the primary circuits as will be understood by those skilled 75 in the art.

A spring member 18 is formed with an offset 19 having its end slotted to straddle roller 15 and bent into beads 20. This offset 19 is inserted in slot 9 with beads 20 resting against the ends of pin 16. The other end of the spring 18 is bent upon itself at 21 and formed into arcuate catches 22 and 23 provided with a terminal finger piece 24. The portion 21 is forced through 80 the aperture 13 so that the portion 22 catches in rear of the fingers 12 and portion 23 fits into notch 14 of arm 8.

A pin passes through a notch in boss 7 to hold the boss and connected parts on the 85 shaft or post 6.

The operation is the same as that of the parts in the ordinary commutator which have been replaced by the above described mechanism, and is thought to be so obvious 100 as not to require further description. In removing the parts, the finger piece 24 is operated to disengage portion 23 from notch 14, then the portion 21 is removed from the spring seat 13 and the spring, pin and roller 105 may then be removed.

While I have described what I deem to be the most desirable embodiment of my invention, it is obvious that many of the details may be varied without in any way de- 110

parting from the spirit of my invention, and I therefore do not limit myself to the exact details of construction herein set forth nor to anything less than the whole of my invention limited only by the appended claims.

What I claim as new and desire to secure by Letters Patent is:—

1. In a device of the class described, the combination of an arm adapted to be secured to a rotary shaft and provided with two pairs of hooked fingers, a contact roller, a pin on which said roller is mounted and provided with flat faces at its end portions adapted to coact with the fingers of one of said pairs so as to be held in seated position and against turning, and a spring member adapted to be seated between the fingers of the other of said pairs of fingers and to press said pin into engagement with the first pair of fingers.

2. In a device of the class described, the combination of an arm adapted to be secured to a rotary shaft and provided with a pin seat and with a spring seat, a contact roller, a pin for said roller adapted to be seated in said pin seat, a spring adapted to be seated in said spring seat and to coact with the extremities of said pin to press said

pin into said pin seat, and means for securing said spring against movement on said arm.

3. In a device of the class described, the combination of an arm adapted to be secured to a rotary shaft and provided with a pin seat, a contact roller, a pin for said roller and adapted to be seated in said pin seat, a spring removably secured to said arm and adapted to coact with the extremities of said pin to force said pin into said seat and maintain said pin in said seat, and means for securing said spring in place on said arm.

4. In a device of the class described, the combination of an arm adapted to be secured to a rotary shaft and provided with a pin seat, a contact roller, a pin for said roller and mounted in said pin seat, and a spring provided at one end with means for maintaining said pin in said seat and at the opposite end with means whereby said spring may be removed from the device and between its ends with means for securing said spring to said arm.

In testimony whereof I have affixed my signature.

OTTO J. HEINZMANN.
